UNITED STATES PATENT OFFICE.

HARRY E. CLOUSER, OF SAN JOSE, CALIFORNIA.

CONCRETE-BUILDING-UNIT-MOLDING MACHINE.

Application filed November 19, 1924. Serial No. 750,776.

This invention relates to the building art and particularly to concrete building unit molding machines of the tamping type.

The primary object of the invention was 5 to evolve a unitary, self-contained unit forming and tamping machine which can be readily transported and set up where it may be found desirable, either at some central point for serving a given locality or immediately at the building site itself where the 10 volume of building units required would justify the same.

Other objects of the invention are to provide an effective and easily controlling tamping 15 assembly; to arrange for an easy delivery of the "mix" to the tamping mold and the carrying back and reusing of any overflow thereof to prevent wastage; and to provide a simple and effective means 20 of removing the finished units from the machine.

These objects I accomplish by means of such structure and relative arrangement of parts as will fully appear by a perusal of the 25 following specification and claims.

In the drawings similar characters of reference indicate corresponding parts on the several views:

Fig. 1 is a front side elevation of the 30 complete apparatus broken away intermediate its ends.

Fig. 2 is a cross section on the line 2—2 of Fig. 1.

Fig. 3 is a partial back view of the 35 machine.

Fig. 4 is a partial top plan view of the same.

Fig. 5 is a fragmentary sectional elevation 40 showing the concrete feeding structure adjacent the unit forming or mold end of the machine.

Fig. 6 is a fragmentary section showing a concrete-mixer gate structure.

Referring now more particularly to the 45 characters of reference on the drawing, the numeral 1 denotes a pair of spaced uprights rigidly connected together at vertically spaced points by horizontal cross beams 2, and suitably braced from the ground by 50 braces 3. The structure thus formed constitutes a rigid framework upon which my improved unit forming structure is mounted, and hereafter designated in toto by the letter A.

Rigidly mounted on the framework at a 55 suitable height and disposed between while

projecting outwardly of the uprights, is a support 4 for a horizontal mold, preferably of the type shown in my Patent 1,567,243, filed November 29, 1924, Serial No. 752,925 60 and which includes a rigid base or table portion 4^a and horizontally movable side members 5 projecting upwardly therefrom.

Projecting outwardly from the uprights 1 are vertical and parallel rods 6 slidably 65 guided in vertically spaced bearing boxes 7 mounted on the outer faces of the uprights 1. Extending between and rigidly secured to the rods 6 in vertically spaced relation are upper and lower rigid crossbars 8 and 9 70 respectively, serving as guides and bearings for a plurality of aligned but independent tappet rods 10 disposed in a vertical plane extending longitudinally of the mold and centrally between the sides 5 thereof. 75

The rods 10 have heads 11 on their upper ends, above the bar 8 and tappets 12 located between the bars 8 and 9, and stamps 13 on their lower ends below the bar 9. The tappets are adapted to be engaged by cams 14 80 mounted on a common horizontal shaft 15 journaled onto the uprights 1 and extending between the rods 6 and 10 and the adjacent faces of the uprights. The cams are of the type commonly employed in stamp mills, 85 and are mounted in staggered relation on the shaft, so that the tappets move up and down in staggered order. The stamps are of rectangular face-area, and are closely aligned with each other. Their total area is substantially equal to the horizontal surface area of the mold as defined by the sides 5, and they are disposed so as to be in vertical alinement with said mold area.

Pivoted onto one of the uprights 1 is a 95 hand lever 16, connected to the bar 9 by a link 17. Attached to the upper bar 8 adjacent the ends thereof are cables 18 or the like which extend over pulleys 19 mounted on top of the uprights. The cables then extend down behind the uprights and have counterweights 20 attached to their lower extremities. 100

The parts are so arranged that when the lever 16 is raised, the bar 8 bears against 105 the heads 11 of the tappet rods, and raises said rods, and of course their stamps and tappets as well, so that the tappets are raised clear of the cams, the stamps being then in common horizontal alinement, and a considerable distance above the mold. This enables the mold to be easily manipulated, and 110

the concrete poured therein; or the finished unit to be removed therefrom. When the mold has been filled with concrete in the manner hereinafter set forth and it is desired to tamp the concrete in order to make a unit of firm character, the lever 16 is lowered until the bar 8 clears the heads 11 and the tappets rest either on their respective cams or on the surface of the concrete in the mold, as the case may be.

The cams (which are preferably in continuous operation) will of course at once act on the lowered tappets and cause the stamps to rise and fall in the well known manner. 15 The tamping operation completed, the stamps are again raised by manipulation of the lever 16 enabling the finished unit to be withdrawn from the mold.

The reason for the use of a battery of intermittently and alternately operating stamps or tampers, instead of applying a continuous pressure to the concrete is because it has been found from experience to be the best practice inasmuch as it gives the proper density and crushing strength to the units, which is not always obtainable under the pressure method, for various reasons known to those skilled in the art.

The concrete is prepared and fed to the mold in the following manner:

Positioned a certain distance away from the tamping unit is a concrete mixer 21 of suitable type, including a horizontal and cylindrical drum 22, open on top, and a beater and mixing mechanism 23 in the drum turnably mounted on a driven shaft 24. Formed as a segment of the drum on one side thereof is a gate 25 (see Fig. 6) rigidly attached to outwardly extending arms 26 mounted on a shaft 27, to which is connected a control lever 28. The shaft 27 is so located relative to the center of the drum that the gate can only open upwardly, as shown in dotted lines in Fig. 6.

45 The mixer-drum discharges, through the gate opening, into a sloping sided sump 29. An endless driven conveyor 30 of suitable form leads from adjacent the bottom of the sump on the side thereof opposite to the gate and in alinement therewith to the tamping machine a certain distance above the mold and stamps, and in a plane to the rear of the uprights 1. The conveyor discharges at its upper end into a chute 31 leading down to a horizontal table 32 positioned just above the top of the mold and extending lengthwise thereof, the front edge of the table overhanging the back side member 5 of the mold but not projecting sufficiently forward to interfere with the movement of the stamps. Walls 33 project upwardly from the sides and back of the table, so that any material thereon can only escape from the front.

60 Completely surrounding the mold in

spaced relation thereto on all sides is a catch basin 34, whose rim is at a level somewhat lower than the bottom of the mold. This basin discharges onto an endless conveyor 35 of suitable form which in turn discharges into a chute 36, which discharges the material from said conveyor 35 into the sump 29 between the conveyor 30 and the gate 25.

In operation, the materials of which the concrete is to be made are placed in the drum 22. When the mixing is completed, the gate 25 is opened, allowing the contents of the drum to discharge into the sump 29. The gate may then be again closed and the mixing operations continued. In the meantime the conveyor 30 draws on the supply in the sump and raises it to the chute 31, from which point it falls by gravity onto the table 32. From this table the concrete is scraped forwardly by the operator in any suitable manner, to cause it to drop into and fill the mold when desired. Any concrete which may happen to miss the mold, or the excess concrete which is leveled off the top of the mold before the tamping operations are commenced, drop into the catch basin 34 from which place the concrete is automatically returned to the sump to be used over.

Thus there is absolutely no waste of concrete. It will also be seen that the operations of the worker handling the actual making of the units are not necessarily co-ordinated with the operations of the workers mixing the concrete. This is because, assuming of course that mixing operations are not halted for an unduly long interval while the remainder of the apparatus is in operation, there will always be a reasonable supply of mixed concrete in the sump 29 for the conveyor 30 to draw from, and consequently there will also be a continuously maintained flow of concrete deposited onto the table 32.

While the amount on the table may be seriously depleted every time the mold is filled, by the time the mold is emptied and again ready for filling, the supply at hand will have been replenished.

While I have shown an apparatus having only a single block mold and tamping unit, I contemplate using a pair of such units fed from a single mixer of sufficient capacity to supply the needs of both. In such cases another conveyor 37 (see Fig. 5) extends from a point adjacent the upper end of the conveyor 30 to the second tamping unit, with a movable gate or apron 38 between the adjacent-ends of said conveyors. This gate is arranged to be manipulated by any suitable means so that the conveyor 30 will either discharge onto the conveyor 37 or into chute 31. The supporting frames A of the two units are also rigidly connected together by horizontal beams 39 extending between said frames.

To drive the cams, conveyor and mixer, I employ a single electric motor 40 mounted on an extension framework 41 projecting from the back and to one side of the frame

5 A of the tamping unit nearest the mixer. This motor drives a shaft 42 parallel to the motor shaft and mounted on the framework A by means of a pulley and belt structure 43.

The motor also is directly connected in 10 driving relation with a shaft 44 mounted on the framework A disposed at right angles to the motor shaft. Mounted on said framework A is another shaft 45 parallel to shaft 42 (which is also parallel to the cam shaft 15) said shafts 42 and 45 being connected by a chain drive 46. A chain drive 47 connects the shafts 15 and 45 in driving relation. The shaft 45 also extends to the further tamping unit structure, if such is used. 15 and similarly drives the cam shaft thereof.

From the shaft 44 a chain drive 48 extends to and drives a shaft 49 mounted on the framework A parallel to the shaft 44. From this shaft 49 a chain drive 50 extends 20 upwardly to drive the upper shaft 30^a of conveyor 30. A chain drive 51 also extends horizontally from the shaft 49 to a similar shaft mounted on the next unit.

It will therefore be seen by reason of the 25 foregoing arrangement of driving connections, the tamping unit or units and their drive means, are entirely self contained and form a unitary structure which may be readily transported from place to place and 30 put in operation immediately without any initial dismantling and subsequent reassembling of any parts of the structure being necessary.

A belt drive 52 extends from the shaft 44 35 to a shaft 53 mounted in connection with the mixer, a reduction gear drive 54 connecting the shaft 53 with the mixer shaft 24. A clutch 55 of suitable character is arranged between the shaft 52 and its belt drive to 40 enable the driving of said shaft to be discontinued at will.

From the upper end of shaft 30^a a chain 45 drive 56 extends to the lower end shaft 35^a of the return conveyor 35. This conveyor, if two tamping units are employed, extends beyond the catch basin 34 of the adjacent tamping unit to the catch basin of the further unit, so as to serve both units in common.

50 From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A concrete building-unit molding machine including a mold to receive the concrete from which the unit is formed, a plurality of stamps arranged in connection with the mold, operating means for said stamps for causing the same to impart a tamping action on the concrete, rods provided with the stamps, vertically movable guide means for the rods, heads on the rods normally clear of the guide means, and means for raising said guide means to cause the same to abut against the heads and raise the rods simultaneously. 70

2. A concrete building-unit molding machine including a mold to receive the concrete from which the unit is formed, a plurality of stamps arranged in connection with the mold, operating means for said stamps for causing the same to impart a tamping action on the concrete, rods provided with the stamps, vertically spaced bars mounted as a unit and in which the rods are slidably guided, heads on the rods, normally clear of the bars, and a hand controlled lever connected to one of said bars for raising the bar unit to cause the same to abut against the heads and raise all the rods simultaneously. 85

3. A concrete building-unit molding machine including a mold to receive the concrete from which the unit is formed, a plurality of stamps arranged in connection with the mold, rods projecting up from the stamps, tappets on the rods, staggered cams engageable intermittently with the tappets, spaced cross bars forming guides for the rods, heads on the rods above the bars, bearing means mounted in fixed relation with the cams, members vertically slidable through said bearing means and connected to the bars to form a unit therewith, and means for raising said unit to cause the upper bar to engage the rod-heads and raise the rods, the heads being normally clear of the cross bar. 100

4. A concrete building unit molding machine comprising separated members for receiving supplies of concrete, means for supporting individual molds disposed adjacent said members, a main concrete receptacle, a conveyor leading from said receptacle to discharge onto one of the members, a second conveyor leading from said first named conveyor to the other member, and means operable at will for enabling concrete on the first conveyor to be discharged onto the second conveyor instead of onto the one member. 115

5. A concrete building unit molding machine comprising separated members for receiving supplies of concrete, means for supporting individual molds disposed adjacent said members, a main concrete receptacle, a 120

conveyor leading from said receptacle to discharge onto one of the members, the rear end of said conveyor being above said member, a second conveyor extending to the other member from a point beyond the rear end of the first conveyor, and an apron associated with the second conveyor and arranged to bridge the space between the con-

veyors to cause the concrete on the first conveyor to be discharged onto the second conveyor instead of onto the member below the first conveyor.

In testimony whereof I affix my signature.

HARRY E. CLOUSER.
